Attorney.

UNITED STATES PATENT OFFICE.

EUGENE D. DUMOND, OF WATERLOO, IOWA.

ROTATABLE WASHBENCH.

1,163,327.

Specification of Letters Patent.

Patented Dec. 7, 1915.

Application filed August 24, 1914. Serial No. 858,385.

To all whom it may concern:

Be it known that I, EUGENE D. DUMOND, a citizen of the United States of America, and a resident of Waterloo, Blackhawk 5 county, Iowa, have invented certain new and useful Improvements in Rotatable Washbenches, of which the following is a specification.

My invention relates to improvements in 10 rotatable supporting means, and the object of my improvement is to furnish a table having a rotatable top, the latter being made in parts arranged to support different objects or receptacles. This object I have 15 accomplished by the means which are herein- after described and claimed and which are illustrated in the accompanying drawings, in which:

Figure 1 is a top plan view of my im- 20 proved rotatable supporting means. Fig. 2 is a side elevation of the same.

Similar numerals of reference denote corresponding parts throughout the several views.

25 The numeral 17 denotes a cylindrical bearing body supported on legs 13.

The numeral 6 denotes a cylindrical up- 30 right whose lower end is rotatably seated in said bearing body. The sleeve 7 is se- cured upon the upright 6 to rest upon the top of the body 17 and is secured by means of a set-screw 9. Said sleeve has an integral annular ratchet rim 10 about its lower end, whose teeth are engaged by a pawl 12, the 35 latter pivoted between lugs 11 on the body 17 and kept in engagement with the ratchet by means of a small spring between the lower end of the pawl and the body 17, not here shown.

40 The numeral 4 denotes a tubular cap fixed on the upper end of the upright 6 and having a vertical stud 5 seated in a triangular body 18. A plurality of annular tubular bodies 1 is secured about the body 18. These 45 bodies are reinforced by cross-braces 3 and supported by arms 8 extending thereto from the sleeve 7. One of the rings 1 has a varied construction in this, that instead of having a brace 3 extending diametrically across it, it is supported by short braces 2 and an inner concentric ring 19.

The numeral 14 denotes a bracket arm se- 50 cured to the cap 4 and having a horizontally disposed disk 15 thereon below and

spaced apart from said ring 19. Said disk 55 15 may serve as a supporting means for a gas burner 16, or the like.

My improved device is primarily intended for supporting a plurality of wash tubs or other receptacles near a washing machine, 60 so that the top thereof may be rotated to shift the receptacles in turn to the place where they are to be used. The heating means 16 may be used to warm the contents of a receptacle placed thereover. 65

Attention is particularly directed to the reentrant angles between the annular bodies 1. This permits a person to stand within these angles in order to get close to tubs or other receptacles supported on said bodies, 70 which is a necessary convenience not possible were the supporting tables not so formed. Attention is also called to the fact that the circular parts 1 are detachably mounted and secured by means of bolt and 75 nut fastenings to their supports 18 and 8, whereby they may be disassembled for convenience in shipping and storing.

Having described my invention, what I 80 claim as new, and desire to secure by Letters Patent, is:

1. In combination, a base having a center-bearing, a standard rotatably mounted in said bearing, a horizontal tubular head mounted upon said standard, horizontal 85 rings detachably supported about said head to have reentrant spaces between adjacent rings to allow the user to pass between them, means for adjustably securing said head in a desired position, and an arm projecting 90 from said standard having a horizontal plate at its outer end located under one of said rings.

2. In combination, a base having a center-bearing, a standard rotatably mounted in 95 said bearing, a plurality of horizontal rings supported about said head, an inner concentric ring located within one of said rings and fixedly connected thereto, and a horizontal plate located below said inner ring 100 and fixedly connected to said standard.

Signed at Waterloo, Iowa, this 6th day of Aug., 1914.

EUGENE D. DUMOND.
